UNITED STATES PATENT OFFICE.

CLINTON M. SEARL, OF PORTSMOUTH, OHIO, ASSIGNOR TO THE VULCAN LAST COMPANY, OF PORTSMOUTH, OHIO, A CORPORATION OF OHIO.

LAST.

Original application filed April 21, 1924, Serial No. 707,796. Divided and this application filed November 24, 1924. Serial No. 751,761.

To all whom it may concern:

Be it known that I, CLINTON M. SEARL, a citizen of the United States, residing at Portsmouth, in the county of Scioto and State of Ohio, have invented certain new and useful Improvements in Lasts, of which the following is a specification, reference being had therein to the accompanying drawing.

10 My invention relates to an improvement in lasts, and is particularly directed to lasts of the divided type—that is to say, to that type of last which is divided into two parts, a toe part and a heel part, movable relatively to each other to collapsed and extended positions. The present application is a division of my application filed April 21, 1924, Serial No. 707,796.

15 It is desirable in lasts of this type that the last be capable of being easily collapsed so that it may be removed from a shoe without injury to the lining of the shoe and without stretching the shoe out of place.

20 In lasting a shoe the last is held upside down—that is, with the sole side uppermost—and inasmuch as a great deal of pressure is put on the toe of the last during the lasting operation, this tends to collapse the last, and consequently one of the objects of my invention is the provision of a construction in which the last is capable of withstanding the stresses to which it is subjected during the lasting operation without collapsing, but may be readily collapsed by the 25 operator when desired.

25 In one form of last now in extensive use, the fore part and heel part are attached to each other by a link attached to the fore part and heel part by pins so located relatively that a line drawn through their centers will fall above the axis on which the last parts move when the last is collapsed and below this point or axis when the last is extended.

30 In such a construction, the greater the distance the pins are below the axis of the last when the last is extended, or the greater the distance they are above the axis of the last when the last is collapsed, the more 35 resistance the last will offer to collapse or extension, but this distance is limited inasmuch as the pins must be located in the last body itself, and in the case of wooden lasts the pins must be kept at an appreciable dis-

tance from the bottom or sole face owing to the danger of splitting the last when the same is in use or when being moved from extended position to collapsed position or vice versa.

40 In the present construction I have provided an arrangement for attaching the two last parts to each other whereby an effect is obtained which is as efficient as the lowering of the pins in the above-outlined construction to the danger point, the resistance to collapse or extension offered by my last being very materially increased, without, however, necessitating placing of any pins at a point where they are likely to cause the 45 last to split.

50 It is one of the especial objects of my invention to provide a last in which the last parts are held together under tension and not simply held in expanded or collapsed position under tension.

55 It is a further object of my invention to hold the last parts together by means employing a lever, with the parts constantly under tension.

60 It is a still further object of my invention to hold the parts of the last together under tension with the parts so arranged that the tension will assume its maximum when the parts are either in their fully expanded or 65 fully collapsed position.

70 It is an additional object of my invention to provide the holding together of the parts under tension and to associate therewith a lever, the parts being so arranged that the tension will achieve its maximum at the 75 completely expanded or collapsed position of the last parts. It will be realized that the tension may be created by a variety of means which may be very compressible or expandible, and that the details of creating 80 this condition are not essential.

85 It is a further object of my invention to provide such mechanism to hold the parts of the last together under tension that it 90 will not be necessary to have resilient links or resilient anchor pins. Such means are eliminated and the same results are obtained.

95 It is a further object of my invention to provide the holding of such parts together 100 under tension and the increasing of this tension at extreme positions together with means to lock the parts in extended position 105

by such tension means to resist the pressure, tending to collapse the last imposed on the bottom of the toe member in constructing the shoe thereon until such tension means is overcome by the operator breaking the last.

5 In the accompanying drawings:—

Fig. 1 is a sectional view showing one embodiment of my invention;

10 Fig. 2 is a similar view of another embodiment.

Referring to the drawings, in Fig. 1, I provide a last comprising a heel part 1 and a toe part 2, divided by an arcuate cut 3. 4 designates a center or bearing pin about 15 which the last parts move when being extended or collapsed, as the case may be, this pin being located at the center of the cut 3. Fastened by this pin is a triangular shaped plate 5, one extremity of the base 20 of which is secured by the pin 4 while the other extremity of the base is secured to the heel part 1 of the last by the pin 6. The apex of the triangular plate 5 is pivotally attached by a pin 7 to the heel or 25 rear end of a link 8. The forward end of this link extends into the toe part of the last where it is pivotally attached by a pin 9 to a triangular shaped plate 10. The forward extremity of this plate is pivoted 30 by a pin 11 to the toe part of the last. Extending longitudinally of the last is a tube 12, slotted at 13 to receive the plate 10, the tube extending from the pin 11 to the pin 4. Within the tube is a spring 35 14 always under compression between the pin 4 and a ball 15 within the tube and which engages one side 16 of the plate 10. This side or edge of the plate is in the form of a cam.

40 With the parts in extended position, as indicated in full lines, the spring 14, which is under compression, tends to rotate the plate 10 about the body pin 11 to move the lever 8 to the left, as viewed in the drawing, to in turn rotate the plate 5 about the center or bearing pin 4. This carries the pin 6 downwardly in a direction to shorten the distance between the pins 6 and 11 to hold the last in extended position under 45 tension. The cam on the plate 10 acts as a lock. When the last is collapsed, the spring 14 tends to actuate the pin 6 in the opposite direction to again shorten the distance between the pins 6 and 11, and 50 hence hold the last parts in collapsed position under tension.

55 In Fig. 2, 17 designates the heel part and 18 the toe part of a last divided by an arcuate cut 19, these two last parts moving 60 or pivoting from extended position to collapsed position, and vice versa, about a bearing pin 20. Secured to the heel part by the pin 20 is a triangular shaped plate 21, one extremity of the base of this plate 65 being attached to said heel part by a pin

22. The other extremity of this plate is pivotally attached by a pin 23 to a link 24. This link extends into the toe part of the last, where it is pivoted at 25 to the forward extremity of the base of a second plate 26 pivoted to the toe part of the last by a pin 27. This last is provided with a longitudinally extending tube 28, within which I mount a spring 29, this spring being held under compression between the bearing pin 20 and a ball 30 which engages the face 31 of plate 26 when the last is extended and the face 32 when the last is collapsed.

20 In this embodiment of my invention, when the parts are in extended position, the action of the spring 29 on the face 31 of the plate 26 tends to swing the pin 22 in a direction to shorten the distance between this pin and the pin 27, thereby holding 25 the last in extended position under tension. Likewise when the last parts are collapsed, these two pins are being forced toward each other to hold the last collapsed 30 under tension.

It will be apparent that I have provided a last structure wherein the last parts are held in extended position and in collapsed position under tension, thereby providing 25 a structure which will successfully withstand accidental collapse or extension of the last parts when the same are in use in the manufacture of shoes. It will be seen also that in my invention I provide a structure in which the force exerted on the last parts to hold the last in extended and in collapsed position is of some magnitude, my improved construction being such, however, that this increase in force is provided without weakening the last. In other words, 100 more power is available for holding the last parts in adjusted position due to my improved structure than is possible in lasts as now manufactured.

105 It will be seen also that I have provided a last structure wherein the last parts are held in extended position and in collapsed position under greatest tension. In other words, the tension under which the last parts are held to each other when the last is extended or when the last is collapsed, as the case may be, is greater than the tension under which the last parts are held when in an intermediate position.

110 Having thus fully described my invention, what I claim as new and desire to secure by Letters Patent is:—

1. In a last of the divided type and comprising a heel part and a toe part, a bearing pin for said last parts, a triangular shaped plate having one extremity secured on said bearing pin, another extremity secured to said heel part, a bearing pin in the toe part, a tube within the heel part and toe part and mounted on said bearing 125 130

pins, a substantially triangular shaped plate pivoted about said bearing pin in the toe part, a link having one end pivotally connected to said plate in the heel part and 5 its other end pivotally connected to the plate in the toe part, and a spring within said tube for rotating the plate within the toe part about the bearing pin in said toe part to thereby maintain the heel part and 10 toe part in extended position and in collapsed position under tension.

2. In a last of the divided type, the combination of a heel part and a toe part, a triangular plate having the forward extremity of its base secured to the heel part 15 of the last at the axis of the last parts and having the rear extremity of its base secured to the heel part of the last, a link

pivotedly attached to the apex of said plate and extending into the toe part of the last, 20 a second triangular plate, the apex of which is attached to said link pivotally and the forward extremity of the base of which is pivoted to the toe part of the last, and a spring interposed between said plates and 25 exerting a pressure on the last-mentioned plate in a direction to tend to shorten the distance between the points of attachment of the two plates to the respective last parts to thereby maintain the last parts in 30 extended position and in collapsed position under tension.

In testimony whereof, I affix my signature.

CLINTON M. SEARL.
